BOOKBINDER

Isidore Spinner, Chicago, and Philip V. Spinner,
Wilmette, Ill.

Application March 11, 1935, Serial No. 10,416

2 Claims. (Cl. 281—19)

This invention relates to improvements in book binders, and more particularly to a binder for spiral bound or like multiring stitched sheets or fillers.

5 The object of the invention is to provide a cover or binder especially adapted to be used in connection with filler sheets or leaves previously bound into book form by the already mentioned spiral binding, thus giving the combination the appearance of a permanently bound volume, while affording the convenience of a replaceable filler.

And in this connection it is to be observed at the outset that the so-called spiral binding differs from the ordinary loose-leaf binding as exemplified by the familiar ring binder, in that the sheets are bound into book form by a spiral binder of stiff wire threaded through marginal perforations, this binder acting to stitch the leaves somewhat loosely together, although with sufficient security to obviate the need for any additional binding. Moreover the spiral binder forms the backbone of the book, and hence is exposed regardless of the covers used which are but perforated sheets of a heavier and/or stiffer material, whereas the ordinary ring binder is a complete cover equipped with two or more split rings passing through holes punched in the sheets. For certain uses, the spiral binding is not objectionable, as for example in making up stenographic note, memorandum and like books of a more or less inexpensive and temporary character, but for the better grade of books, such as ledgers, diaries and books of permanent record, there is a demand for the more conventional style of binding, in combination with the spiral type of binding for the contents, and the present disclosure seeks to provide such a combination.

40 With this introduction to the subject matter of the invention, a preferred embodiment thereof will be described in connection with the accompanying drawing, in which

Figure 1 is a view in elevation of a spiral bound filler mounted within a cover or binder.

45 Figure 2 is a view in end elevation of the combination shown in Figure 1.

Figures 3 and 4 are enlarged detail views in cross section taken on lines 3—3 and 4—4, respectively, of Figure 1.

50 Figure 5 is a view in side elevation of the parts of the fastening device.

Figure 6 is a perspective view of the fastening device with the rod partly removed.

55 The completely assembled book comprises a

cover member 1 and the filler 2 therefor, consisting of a sheaf of leaves or printed leaves, as the case may be. As already explained, the filler is a self-contained unit or bound book by reason of the spiral binding or stitching 3 along one edge, although in this instance, the outer cover sheets would be omitted. Manifestly, then, the filler sheets are bound without regard to their subsequent mounting within the cover or binder except perhaps for the character of the 10 cover sheets used, if any. In any case, the sheets are first stacked and punched along the edges to be bound, with a multiplicity of small holes or perforations 4 spaced fairly close together and near the edge of the sheets. Then 15 the helix or spiral of stiff wire 3 is threaded lengthwise through the perforations, the spacing of the perforations being the same as the pitch of the helix, so that by starting at one end and turning the spiral in the proper direction, it threads itself throughout the length of the sheets, whereupon the extremities 3^a, 3^a are bent back and inwardly so as to lock the helix against working endwise and out of the perforations. It will be noted that the character of the spiral 3 is slightly greater than the thickness of the bound sheets, with the result 20 that at least one-half the circumference of the spiral is exposed along the bound edge, and a considerable portion of the space included by 25 the spiral is open beyond the edges of the leaves.

The cover or binder 1 may be of any suitable material and construction, consisting of front and back cover sections 5 and 6, and a backbone 7 having flexibly hinged connections with the cover sections on either side. By preference, the binder is slightly larger than the filler or contents so that marginal portions thereof project beyond the three sides of the filler as shown 40 in Figure 1. Moreover, the width of the backbone of the binder is substantially equal to the thickness of the filler, or more accurately, the diameter of the spiral binding wire 3 which in turn is slightly greater than the thickness of the 45 sheets in order to permit them to be turned easily without binding.

Now, extending the length of the backbone on the inside of the binder is a flat metal bar 8 terminating a short distance inwardly from each 50 end of said backbone in short upstanding brackets 8^a, 8^a bent at right angles to the main body of the bar, which is riveted as at 9, Figure 3, at two or more points along the backbone of the binder. By preference the backbone is rein- 55

forced by a suitable stiffening strip 7^a through which the rivets are driven, their heads being preferably concealed beneath the material covering the outside of the binder.

5 Located centrally of the upstanding brackets 8^a at each end of the bar 8 are relatively large holes 8^b , their centers being spaced well outwardly from the base of the brackets, so that there will be ample clearance between the holes and the body of the bar. Extending lengthwise of the bar and insertable endwise through the end brackets thereof is a round metal rod, 10 somewhat smaller in diameter than that of the holes 8^b , in fact, the rod is just large enough to be quite stiff without adding unnecessary weight. The length of the rod is slightly greater than the bar 8 so that each end projects a short distance beyond the end brackets 8^a , 8^a when the rod is in place. The ends of the rod are threaded to receive cylindric shaped thumb nuts 11 having an enlarged milled head 11^a and a boss or reduced extension 11^b , the former being greater in diameter than that of the holes 8^b in the brackets 8^a , and the latter slightly less, so that on mounting the nuts on the outer ends of the rod the boss 11^b will pass through the holes 8^b bringing the shoulders formed by the heads 11^a flush against the outer faces of the brackets 8^a .

20 As additional supporting means for the rod 10 , the bar is provided with integral lugs 12 stamped out and bent upwardly at points spaced inwardly from the ends thereof. As shown in Figure 5, there are two of these lugs approximately half way between the center and ends of the bar, although the number and spacing of these lugs may be varied in different sizes of binders. The primary purpose of these lugs is to support the rod intermediate its ends, and hence the lugs have holes 12^a in alignment with those in the end brackets of the bar, but smaller in diameter, that is, just large enough to permit the rod to pass through. Another and equally important function of these lugs is to act as stop members to hold the spiral bound filler against movement in the binder, as will presently be noted.

Now, assuming that the filler is to be inserted in the binder, it is only necessary to remove the nut from one end of the rod and withdraw it endwise from its supporting bar, whereupon the filler 2 is placed in position with the spiral binding extending lengthwise of the bar and between the end brackets 8^a , 8^a . The rod is then replaced by threading the free end through the aligned holes in the brackets 8^a and lugs 12 , and at the same time through the open space extending the length of the spiral 3 beyond the edges of the leaves. And finally, to securely fasten the filler in the binder, one or both nuts are drawn up tightly after inserting the bushing-like extensions through the large holes in the end brackets as shown in Figure 5. This places both the bar and the rod under tension, thus making the complete fastening device rigid and securing the parts against loosening. Moreover, by this arrangement the heads of the thumb nuts

are located inwardly from the edges of the binder, so none of the parts are exposed when the binder is closed.

And finally, the lugs 12 projecting between the turns of the spiral will invariably bear against the nearest turn, thus preventing any appreciable endwise shifting of the filler lengthwise on the rod, it being observed particularly that while the brackets 8^a at the ends of the bar would ordinarily act in this capacity, in practice the extreme ends of the helix usually stop short of the edges of the filler and frequently there is some discrepancy in the lengths of the spiral in different fillers of the same page size. Hence if contact between the ends of the spiral and the end brackets 8^a were the only means for holding the filler securely in the binder, there would invariably be some end play which would interfere with the free turning of the pages. The lugs, therefore, assist materially in properly centering the filler in the binder and holding it against subsequent movement on the rod.

Thus for mounting spiral bound sheafs or fillers in separate binders, the fastening device herein disclosed affords a very practical means of meeting the demand for a book having the appearance of a permanently bound book, but yet having the convenience of a renewable filler.

We claim as our invention:

1. In a book binder, the combination with a 30 filler consisting of leaves bound together along one edge with a spiral binding of stiff wire, of a binder comprising cover sections and a backbone, a bar extending lengthwise of said backbone and having its end portions bent to provide brackets 35 projecting at right angles to the inner face of said backbone adjacent the ends thereof, a rod removably insertable through holes in said brackets and adapted to pass through said spiral binding when the same is positioned lengthwise 40 of said backbone between said brackets, and a lug projecting from said bar intermediate its ends and having a hole in alignment with the holes in said brackets, said lug acting to support said rod intermediate its ends and to project between adjacent turns of said spiral binding.

2. In a book binder, the combination with a 50 filler consisting of leaves bound together along one edge with a spiral binding of stiff wire, of a binder comprising cover sections and a backbone, a bar extending lengthwise of said backbone and having its end portions bent to provide brackets projecting at right angles to the inner face of said backbone adjacent the ends thereof, and 55 a rod provided with a removable nut at one end, permitting the same to be inserted endwise through holes in said brackets and said spiral binding when the same is positioned lengthwise of said backbone between said brackets, said bar 60 being provided with integral lugs spaced apart at intervals intermediate its ends and projecting between adjacent turns of said binding to support said rod.
